UNITED STATES PATENT OFFICE.

PATRICK SLENSBY, OF BROOKLYN, NEW YORK.

DESIGN FOR A NEEDLE-THREADER FRAME.

SPECIFICATION forming part of Design No. 21,600, dated May 31, 1892.

Application filed April 24, 1891. Serial No. 390,336. Term of patent 14 years.

To all whom it may concern:

Be it known that I, PATRICK SLENSBY, a citizen of the United States, residing at Brooklyn, in the county of Kings and State of New York, have invented and produced a new and original Design for a Needle-Threader Main Frame, of which the following is a full, clear, and exact specification, reference being had to the accompanying drawings, in which—

10 Figure 1 is an edge view, and Fig. 2 is a perspective view, of a needle-threader frame, showing my design.

The leading feature of my design consists in the edge contour most clearly shown in 15 Fig. 1. At its rear edge, or edge to the left

in Fig. 1, is represented, beginning at the top, the vertical line 1, below which are produced the inclined lines 2 and 3 and the vertical line 4. On the front edge of the frame are produced the vertical lines 5 and 6 and the inclined line 7, merging at its upper end in line 5 and connected at its lower edge by the line 8 with the vertical line 6. 20

I claim—

The design for a needle - threader main 25 frame herein shown and described.

PATRICK SLENSBY.
